CLAIM

The ornamental design for a label, as shown and described.

DESCRIPTION

The patent or patent application file contains at least one drawing executed in color. Copies of this patent or patent application publication with color drawing will be provided by the Office upon request and payment of the necessary fee.

FIG. 1 is a front view of a first embodiment of a label. FIG. 2 is a front view of a second embodiment of a label. FIG. 3 is a front view of a third embodiment of a label; and, FIG. 4 is a front view of a fourth embodiment of a label. The broken line portion of the figure drawings is included to show portions of the article that forms no part of the claimed design.

1 Claim, 2 Drawing Sheets
